INVENTOR

Milton P. Higgins

UNITED STATES PATENT OFFICE.

MILTON P. HIGGINS, OF WORCESTER, MASSACHUSETTS.

FURNACE CHARGING AND DISCHARGING APPARATUS.

SPECIFICATION forming part of Letters Patent No. 436,856, dated September 23, 1890.

Application filed April 20, 1888. Serial No. 271,311. (No model.)

To all whom it may concern:

Be it known that I, MILTON P. HIGGINS, a citizen of the United States, residing in the city and county of Worcester, State of Massachusetts, have invented a new and useful Furnace Charging and Discharging Machine, of which the following is a specification.

The customary method of drawing heavy hot blooms from furnaces has been to first 10 grasp them with the tongs, then for several men to seize the chain or rope attached to the tongs and haul them out by main strength. This having to be done with the bloom at a 15 glowing heat exposes the men to the intense heat while making great effort, and, though putting the cold bloom into the furnace or "charging" has no heat from the bloom, yet the mouth of the furnace into which the 20 heavy bloom or fagot has to be pushed on the "peel" throws out a hot glow that the men cannot stand long.

To overcome all difficulties and relieve the men of exposure to such intense heat and to do the work rapidly and effectually with but 25 few men are the main objects of my invention. Its nature is shown by the following description and accompanying drawings, in which—

Figure 1 is a plan; Fig. 2, a front elevation; 30 Fig. 3, an end view as seen from the right of Fig. 1, with the chain and pulley as in the act of charging or pulling the bloom and peel in.

In Fig. 1, H H H are the doors of the furnace. A is the frame of the machine, consisting of two sides or ways, with a slide B between them, and having a hydraulic cylinder C beneath one end, with a plunger O attached, as by bracket N, to the slide B, the cylinder 35 having connections to the valve D, provided with lever-connection to operating-rod F and suitable pipes P and Q for supply and discharge. On the top of the frame A and on the side next the furnaces are the pulleys a 40 and similar ones b on the slide B, and on the other side of the frame A are the chain-stoppers J, these being arranged so that the chain G

can be dropped into any one between its jaws and hold and yet readily lifted out to release it, the frame A being provided with legs to 50 make its top about the same height as the furnace-doors. To the slide B is attached a chain passing over a pulley, and to which the weight is attached sufficient to draw back the plunger and slide B to the starting-place, when 55 the valve D is set so that the water in the cylinder can escape; or a spring might, in some cases, be preferable to do the same work.

In operation, to draw out a bloom the tongs are applied with the chain attached, as shown 60 in Fig. 1, and the chain passed one-quarter round a pulley, as at a, then one-half round the one b and a link brought down into the stop J; or with the slide B clear back the pulley b will be beyond a, allowing the chain to 65 be brought directly between them to the stop J. Then the water being let onto the cylinder, its plunger is forced out, carrying the slide B and drawing the bloom I out as far as desired. 70

For recharging, a pulley m is arranged to slide on a bar L, placed below the furnace-doors, so arranged that by moving it along the same pulley can be brought in line with any door, and the chain is passed over the 75 pulley and fastened to the end of the peel S, on which the fagot or cold bloom K has been placed, as shown in Fig. 3. The other end of the chain being then applied to the slide as before and the plunger operated, the peel, 80 with its load, is forced into the furnace, as desired.

Having thus fully described my invention, what I claim as new, and desire to secure by Letters Patent, is— 85

In a furnace charging and discharging apparatus, the combination, with the ways, slide, and pulleys, of the tongs, chain, and mechanism for moving the slide, substantially as described.

MILTON P. HIGGINS.
